(57) **CLAIM**

The ornamental design for a motor boat, as shown and described.

DESCRIPTION

FIG. 1 is a left rear perspective view of a first embodiment of a motor boat showing our new design;

FIG. 2 is a right side elevational view of the motor boat shown in FIG. 1;

FIG. 3 is a left side elevational view of the motor boat shown in FIGS. 1 and 2;

FIG. 4 is a top view of the motor boat shown in FIGS. 1-3;

FIG. 5 is a bottom view of the motor boat shown in FIGS. 1-4;

FIG. 6 is a front elevational view of the motor boat shown in FIGS. 1-5;

FIG. 7 is a rear elevational view of the motor boat shown in FIGS. 1-6;

FIG. 8 is an environmental, left side elevational view with the broken line showing of a flybridge structure with a bimini top being for illustrative purposes only and forming no part of the claimed design;

FIG. 9 is a left rear perspective view of a second embodiment of a motor boat showing our new design, the third embodiment having a modified side window configuration;

FIG. 10 is a left rear perspective view of a third embodiment of a motor boat showing our new design, the fourth embodiment being a stretched version of the embodiment shown in FIG. 9;

FIG. 11 is a left rear perspective view of a fourth embodiment of a motor boat showing our new design, the fifth embodiment being a stretched version of the embodiment shown in FIGS. 1-7; and,

FIG. 12 is a left side elevational view of the motor boat shown in FIG. 11.

The dashed line renderings of the flybridge structure and bimini top in FIG. 8 are for illustrative purposes only and form no part of the claimed design.
